UNITED STATES PATENT OFFICE.

LEONARD SHOGRAN, OF INDIANAPOLIS, INDIANA, ASSIGNOR OF ONE-HALF TO
CHARLES H. FELTMAN, OF CHICAGO, ILLINOIS.

DISPLAY-FIXTURE.

1,333,042.

Specification of Letters Patent.

Patented Mar. 9, 1920.

Application filed December 27, 1917. Serial No. 209,066.

To all whom it may concern:

Be it known that I, LEONARD SHOGRAN, a citizen of the United States, and a resident of Indianapolis, county of Marion, and State of Indiana, have invented a certain new and useful Display-Fixture; and I do hereby declare that the following is a full, clear, and exact description thereof, reference being had to the accompanying drawings, in which like letters refer to like parts.

This invention relates to display fixtures and primarily to that class adapted to be placed in windows, show cases or other convenient points for displaying wares of any preferred class or design, but in this instance is shown as displaying shoes, and the object of the invention is the provision of a bracket and means for temporarily connecting the same to a supporting base or other member. A further feature of the invention is the provision of means for holding a shoe either in tilted or horizontal position.

A further feature of the invention is the construction of a bracket wherein the same may be made of a single piece of metal and so bent as to form a securing part as well as a shoe supporting part. A further feature of the invention is the provision of a pedestal and means for quickly attaching or detaching the bracket supporting member thereon.

The full nature of the invention will be understood from the accompanying drawings and following description and claims.

Figure 1 is a side elevation of a pedestal showing two of the brackets attached thereto and in use. Fig. 2 is a side elevation of the upper end of the pedestal and platform thereon showing one form of article supporting bracket attached thereto. Fig. 3 is a sectional view as seen on line 3—3 of Fig. 1. Fig. 4 is a perspective view of one form of bracket removed from its support and Fig. 5 is a sectional view as seen on line 5—5 of Fig. 1, showing the manner of attaching the platform to the pedestal.

Referring to the drawings in which similar reference numerals designate corresponding parts throughout the several views, 1 indicates a pedestal and 2 indicates a platform, said parts being preferably constructed of glass so as to render the same more attractive, although it will be understood that said parts may be of any suitable material. The upper end of the pedestal 1 is provided with

a head 3 which is preferably hexagonal and larger in diameter than the adjoining portion of the pedestal so as to provide an overhanging portion 4 with which engages the inturned ends 5 of a clip 6, said clip extending over the platform and serving to hold the platform in fixed relation with the pedestal owing to the compression exerted by the inturned ends 5 on the under face of the overhanging portion 4. The platform 60 2 may be constructed in any preferred shape, but for the purpose of displaying shoes or similar articles the platform is made rectangular and may be extended equally beyond the head 3 or a greater portion thereof 70 extended to one side of the head than the other, as shown in Fig. 2.

Cooperating with the platform 2 are brackets which may be formed in various designs 7, 8 and 9. The various brackets are 75 preferably formed from a single piece of flat metal, each comprising a vertical portion 10 and a horizontal portion 11, the bracket shown as 7 having a portion bent substantially U-shaped to form a clamp 12, the bent 80 end of the clamp being preferably slightly constricted so that when engaged with the edge of the platform the springy nature of the material of which the bracket is made 85 will cause the clamp to bind on the platform and thus securely hold the bracket in position. The clamps 13 and 14 of the forms of bracket shown at 8 and 9, instead of being bent out of the vertical portion 10 of the bracket, are formed by bending the horizontal sections 11 substantially U-shaped, although the action of the clamps are identical. Some of the brackets as shown in Figs. 1, 3 and 4, are provided with an elongated 90 horizontal portion 11, said elongated portion forming rests for the toe of the shoe 95 15. In order to hold the shoe in position on the brackets and at the same time dispose them at an inclination, the outer ends of the vertical portions of the brackets are provided with tongues 16 and rests 17 and by hooking the heel of the shoe over the tongue 16 and resting the same upon the rests 17, the shoe will be securely held in position on the bracket. The tongues 16 and rests 17 100 105 may be formed in various ways, but in the present instance the outer end of the vertical portion 10 is enlarged and then slotted and part of the slotted portions bent over to form the rests.

In addition to forming supports for shoes the position of the brackets, especially that form shown at 9, may be reversed on the platform and by bending the rests 17 to 5 exact right angles with the vertical portion 10, various articles may be supported thereon. In applying the device to use, the platform 2 is placed over the head end of the pedestal, and a clip 6 then forced into engagement with the pedestal so as to clamp the platform into position and as previously stated the platform may extend a uniform distance on each side of the pedestal, or a greater portion extended to one side 10 than the other. The clamp portions of the brackets are then introduced over the edges of the platform and any number of the brackets may be used in connection with the edge of the platform so long as they are so 15 distributed as to equalize the weight upon the pedestal to prevent the same from tipping over. The horizontal portions of the brackets 7 and 8 form a rest for the toe portion of the shoe while the bracket 9 is preferably attached to the end of the platform 2, so that said platform will form a rest for the toe end of the shoe and said brackets may be turned or positioned at various angles with respect to the platform so as to 20 properly exhibit the articles placed thereon.

Instead of using the pedestal and platform herein shown, it will be readily understood that the brackets may be used with various supports, such as glass counters for 25 show cases, and the glass shelves now commonly used in show windows for exhibiting shoes or the like.

It will likewise be seen that if it is desired to support the shoe in a horizontal 30 plane, the elongated horizontal portions 11

of the brackets 7 and 8 may be bent upwardly until the free ends are brought into horizontal alinement with the rests 17, thus adapting the bracket for supporting the shoe either at an inclination or in a horizontal position. 45

The invention claimed is:—

1. A display fixture, comprising a bracket having a vertical supporting portion and a horizontal supporting portion said vertical portion having a tongue and rests at opposite sides of the tongue, and a securing clamp formed by bending portions of the bracket for securing the bracket to an object. 50

2. A display fixture, comprising a bracket having a horizontal portion and a vertical portion, the upper end of said vertical portion being enlarged and having slits therein, the outer slitted portions being bent rearwardly and downwardly to form rests, the other slitted portion forming a tongue, and an integral clamp formed by bending parts of the bracket. 60

3. A display fixture for shoes, comprising a flat one-piece bracket having a portion thereof bent to substantially U-shape, to form a clamp for frictionally engaging the bracket with a support, one end of the bracket having longitudinally extending 70 slits, the central slitted portion forming a tongue for engagement with the front portion of the heel of the shoe, the other slitted portions being bent rearwardly and downwardly to form a rest for the heel of the 75 shoe.

In witness whereof I have hereunto affixed my signature.

LEONARD SHOGREN.
